(57)

CLAIM

The ornamental design for a treat dispensing pet toy, as shown and described.

DESCRIPTION

FIG. 1 is a perspective view of a treat dispensing pet toy showing my new design;

FIG. 2 is a front side view thereof;

FIG. 3 is a left side view thereof;

FIG. 4 is a back side view;

FIG. 5 is a right side view thereof;

FIG. 6 is a top view thereof; and,

FIG. 7 is a bottom view thereof.

The broken lines are included for the purpose of illustrating unclaimed portions of the design and form no part thereof.

1 Claim, 7 Drawing Sheets(56)
